Frederic L. Wanklyn.

Inventor.

William F. McLean

Attorney.

UNITED STATES PATENT OFFICE.

FREDERIC LUMBE WANKLYN, OF MONTREAL, QUEBEC, CANADA.

TORPEDO.

Application filed December 31, 1920. Serial No. 434,386.

To all whom it may concern:

Be it known that I, FREDERIC L. WANKLYN, a subject of the King of Great Britain, of the city of Montreal, Province of Quebec, 5 Dominion of Canada, have invented certain new and useful Improvements in Torpedoes; and I do hereby declare that the following is a full, clear, and exact description thereof.

10 My invention relates particularly to torpedoes for use on a railway for signalling an approaching train when the train is out of reach of telegraphic and telephonic communication, and has particular reference to 15 the railway track torpedo disclosed in my United States patent granted October 19th, 1920, under No. 1,355,871. The present invention has for its object to simplify the manufacture of this type of torpedo and reduce to a minimum the personal danger 20 from flying parts when the torpedo is exploded; and its object is furthermore to increase the capacity of the torpedo to give warning of danger ahead, and further improve the device by facilitating the assembling and water-proofing of the parts and rendering the complete torpedo more impervious. The aim of the invention is also 25 to enhance its resistance to displacement 30 along the rail.

The present invention consists in the construction and particular arrangement of parts hereinafter specified.

The improved torpedo consists of a carrier with integral rail-clips of steel, brass or other suitable metal, the carrier having secured thereto a container for smell producing, detonating and smoke and flash producing elements, the container being 40 adapted to be readily hermetically sealed. The means of fastening the container to the carrier is such that the entire explosion takes place above all the metal in the torpedo, thus eliminating any danger of the 45 metal parts being a source of personal danger when the explosion takes place. The means for fastening the container to the carrier consists of folding the ends of the container from both side edges inwards and 50 then folding under to be clipped into folded ends of the carrier underneath the same; or the ends of the container may be folded under itself above the carrier and fastened to the carrier near its ends by diminutive fastenings.

55 After the container is thus closed the de-

vice is treated with a water-proofing composition then sprinkled with sand while wet and finally dried. It is preferable to pass the complete torpedo through a bath and then after sanding it pass it into a steam heated drying chamber after which it is ready for inspection, and to be packed for shipment to the consumer. The sanding of the torpedo enhances its resistance to displacement along the rail.

For full comprehension, however, of my invention, reference must be had to the accompanying drawings in which similar reference characters indicate the same parts, 70 and wherein:

Figure 1 is a perspective view of the underside of a torpedo constructed according to my invention and illustrating the ends of the container folded beneath the carrier and 75 crimped between the folded ends thereof;

Figure 2 is a transverse sectional view of the torpedo illustrated in Figure 1 in position upon the rail;

Figure 3 is a plan view of the underside 80 of the carrier illustrating in dotted lines the manner of folding the ends;

Figure 4 is a view similar to Figure 1 illustrating a modified form of carrier and means securing the ends of the container 85 thereof;

Figure 5 is a view similar to Figure 4 illustrating a further modification;

Figure 6 is a fragmentary side elevation drawn to a preferred scale of one end of 90 the torpedo illustrating the manner in which the container is secured to the carrier in Figure 1; and

Figures 7, 8 and 9 are detail fragmentary views illustrating the manner of folding 95 the container utilized in the construction shown in Figure 1.

In order to produce my improved torpedo the carrier 2 and clips 3 are struck from the same piece of metal and the ends 100 of the carrier are formed to afford means for fastening the container to it by either having its ends crimped as at 4 and turned beneath it as shown in Figures 1 and 6, or the ends may be perforated to receive eyelets 5 or other diminutive fastening devices. The carrier may also be cut away to reduce the metal required to present either of the forms shown in Figures 4 or 5, each form being of the nature of a cross the arms of 110 which in one case (Fig. 1) are widened.

In order to provide an effective water-

proof non-metallic closure of the ends of the container 6 such ends have their corners folded inwardly as shown in Figure 7 and the end folded back upon the body as in Figure 8 and given a second fold as in Figure 9. This container as thus folded has its folded ends fastened to the ends of the carrier by the diminutive fastening devices 5. The ends of the container need not be folded upon itself when the carrier of Figure 1 is employed but may be closed in any suitable way and inserted into the crimps after which the crimps are compressed, thus hermetically sealing these ends.

15 The device as completed as shown in Figures 1 and 6 or Figures 4, 5, 7, 8 and 9 is then treated with a waterproofing composition, sprinkled with sand while wet and finally dried.

20 The container illustrated is of oblong form but may be square, elliptic, circular or any other form required without departing from the spirit of my invention.

Within the container there is an envelope 12, a tablet 13 and an envelope 14, the relative dimensions of the envelopes, tablet and container being such that the container is completely filled when charged. The envelope 12 contains a smoke producing substance which is of a nature to produce a pungent odor on ignition or if desired this smoke producing substance may be mixed with another substance capable of producing a pungent odor. Tablet 13 is composed of 30 an explosive or detonating and smoke producing substance and the envelope 14 is charged with a flash producing substance.

An important feature of the invention is the structure which places the explosive 40 above all metal parts, the beneficial effect being that no personal damage can be done, there being no metal parts flung about by the explosion.

Furthermore the flash accompanying the 45 detonation will attract the attention of the engine driver even if the vibration of the train or the sounding of the whistle should happen to drown the sound of the explosion and the smoke will have the same effect if 50 bright sunlight prevails. The pungent odor adds an element of safety.

What I claim is as follows:

1. A railway track torpedo consisting of the combination with a container and means 55 for fastening the same to a rail head; of a detonator and a smoke-producing substance.

2. A railway track torpedo consisting of the combination with a container and means for fastening the same to a rail head; of a 60 detonator, a smoke-producing substance and a flash-light powder.

3. A railway track torpedo consisting of the combination with a container and means for fastening the same to a rail head; of a 65 detonator, a smoke-producing substance, and

an inflammable powder producing a pungent odor on ignition.

4. A railway track torpedo consisting of the combination with a container and means for fastening the same to a rail head, of a 70 detonator, a smoke-producing substance, a flash-light powder and an inflammable powder producing a pungent odor on ignition.

5. A railway track torpedo consisting of a metal carrier, means for securing the carrier to the rail head, a container having relatively short folded under ends and containing a detonator and a diminutive fastening 75 securing each end of the container to the respective ends of the carrier.

6. A railway track torpedo consisting of a metal carrier, spring clips formed integrally with the carrier and adapted to secure the latter to a rail head, a container containing a detonator and a diminutive fastening 80 securing each end of the container to the respective ends of the carrier.

7. A railway track torpedo consisting of a metal carrier, means for securing the carrier to the rail head, a container containing a detonator the ends of said container being folded back upon themselves and a diminutive fastening securing each folded end to the respective ends of the carrier.

8. A railway track torpedo consisting of a metal carrier, means for securing the carrier to the rail head, a container containing a detonator the ends of said container being folded back upon themselves, and a rivet 85 securing each folded end to the respective ends of the carrier.

9. A railway track torpedo consisting of a metal carrier, spring clips formed integrally with the carrier for securing the latter to a rail head, a container containing a 90 detonator, the ends of said container being folded back upon themselves, and a rivet securing each folded end to the respective ends of the carrier.

10. A railway track torpedo consisting of a metal carrier, means for securing the carrier to the rail head, a container having relatively short folded under ends and containing a detonator and a diminutive fastening 105 securing each end of the container to the respective ends of the carrier.

11. A railway track torpedo consisting of a metal carrier, spring clips formed integrally with the carrier and adapted to secure the latter to a rail head, a container having relatively short folded under ends and containing a detonator and a diminutive fastening 110 securing each end of the container to the respective ends of the carrier.

12. A railway track torpedo consisting of a metal carrier, means for securing the carrier to a rail head, a container having relatively short folded under ends and containing a detonator the ends of said container being folded back underneath the same and 115

a diminutive fastening securing each folded end to the respective ends of the carrier.

13. A railway track torpedo consisting of a metal carrier, means for securing the carrier to the rail head, a container having relatively short folded under ends and containing a detonator the ends of said container being folded back underneath the same and a rivet securing each folded end to the respective ends of the carrier.

14. A railway track torpedo consisting of a metal carrier, spring clips formed integrally with the carrier for securing the lat-

ter to a rail head, a container having relatively short folded under ends and containing a detonator, the ends of said container being folded back underneath the same and a rivet securing each folded end to the respective ends of the carrier.

In testimony whereof I have signed my name to this specification in the presence of two witnesses.

FREDERIC LUMB WANKLYN.
